(No Model.)

E. B. CORNELL.

AIR INJECTING DEVICE FOR BOILER FURNACES.

No. 380,475.

Patented Apr. 3, 1888.

ATTORNEY.

UNITED STATES PATENT OFFICE.

ELIJAH B. CORNELL, OF PHILADELPHIA, PENNSYLVANIA.

AIR-INJECTING DEVICE FOR BOILER-FURNACES.

SPECIFICATION forming part of Letters Patent No. 380,475, dated April 3, 1888.

Application filed October 12, 1887. Serial No. 252,139. (No model.)

To all whom it may concern:

Be it known that I, ELIJAH B. CORNELL, a citizen of the United States, residing at Philadelphia, in the county of Philadelphia and State of Pennsylvania, have invented certain new and useful Improvements in Air-Injecting Devices for Boiler-Furnaces, of which the following is a specification.

My invention has relation generally to air-injectors for feeding a draft of air to the fire-boxes of locomotive or other boilers for the purpose of insuring the consumption of those products of combustion which are not consumed on account of insufficient draft, and which escape unburned to the stack, and particularly to that form of injector shown and claimed in Letters Patent of the United States No. 287,754, dated October 30, 1883.

My invention has for its object to subject the steam-supply used for operating said injectors to the direct action of the heat of the fire-box before said supply passes to the injector, so as to raise the temperature of said steam to a degree of heat varying from 800° to 1,000°, in order to admit of it taking a gaseous form; or, in other words, the steam is not only superheated but resolved into its gaseous elements to form a hydrogen or water gas, which, while it is not a fixed gas, yet ignites and burns along with the air injected by it into the fire-box, whereby the objections arising from the use in the fire-box of steam that is more or less wet are avoided, greater economy in the use of fuel is secured, more steam is generated in the boiler than is done when natural draft alone is depended upon, a uniform distribution of heat in the fire-box is secured, and the boiler is not in any way injured.

My invention accordingly consists of the combination, construction, and arrangement of parts as hereinafter described and claimed, having reference particularly to a superheater or coil of pipe located so as to be subjected to the most intense heat of the fire-box, a steam-pipe connection between one end of said coil and the boiler, or its dome preferably, an air-injector located, preferably, in the ash-pit, and a pipe-connection between the injector and the superheater, which pipe-connection is of a diameter much less than that of the superheater-coils to provide an outlet for the latter, which

outlet in cross section is of less area than that of the superheater, whereby the steam passing into the latter is subjected to back-pressure to retard its passage through the superheater until the heat in the fire-box more or less resolves it into its gaseous elements.

Referring to the accompanying drawings, which form a part hereof, Figure 1 represents an elevation, partly sectional, of a locomotive boiler, furnace, and fire-box, showing a form of air-injector, superheater, and pipe-connections arranged for operation in accordance with my invention; Fig. 2, a perspective of the superheater-injector detached from the boiler-furnace; and Fig. 3 is a section through the length of the injector.

A represents a locomotive or other boiler; B, its fire box; C, the ash-pit; D, an air-injector located in the ash-pit in any suitable manner. This injector may be of any desired form; but I prefer that shown, described, and claimed in the above-mentioned patent.

The injector is preferably provided at its outlet end with a deflector, d, for throwing the air downwardly into the ash-pit to effect a distribution of the injected air throughout the ash-pit before passing to the fire-box, as set forth and claimed by me in United States Letters Patent No. 353,351 and dated November 30, 1886.

E represents a superheater coil or box of any desired or suitable form, which is located in the fire-box adjacent to the flue-sheet, as shown; or it may be otherwise located, as desired, varying to suit different types of furnaces, and in all cases so located as to be subject to the most intense heat generated in the furnace or fire-box. It has a pipe-connection, e, with the boiler, or preferably with its dome a, and this pipe is provided with a valve, e', suitably located for cutting off the steam-supply from and admitting it to the superheater.

From the outlet end e² of the superheater leads a pipe, e³, which has connection with the cut-off pipe of the injector D, which cut-off pipe d' forms the supply-pipe for the form of the injector shown, and a valve for closing the communication between the injector and its steam or other supply, as fully described in said first-named patent.

The pipe e³ is of less diameter than that of

the coils of the superheater, so that the steam in passing through the latter is retarded in its flow to subject it as long as possible to the intense heat in the fire-box to resolve it into its 5 gaseous elements and produce a hydrogen or water gas for operating the injector, which gas also ignites and burns in the fire-box to increase the combustion.

As the heat generated in the fire box is above 10 from 800° or 1,000°, (more or less,) the steam in the superheater located in the fire-box is rapidly converted into gas, and it being of a high degree of temperature the pipes e^2 and e^3 become correspondingly hot to maintain the gas 15 in a more or less fixed condition until it passes through the injector and into the fire-box.

The gas generated as above described does not ignite at low temperatures. Hence all danger of explosion in the boiler-room is avoided.

20 I do not confine my invention to the construction and arrangement of details, as it is evident that the said details may be greatly varied without departing from the spirit of my invention.

25 I do not broadly claim a superheater connected with the boiler and the ash-pit for the purpose of supplying superheated steam to the fire, as such devices are old. My device differs from such construction in that in the latter 30 the superheated steam is passed into the fire-box without disassociating the hydrogen from the oxygen, whereas in my device the flow of steam from the superheater is retarded in such manner as to disassociate the hydrogen 35 from the oxygen which is taken up by the iron, while the hydrogen is passed directly to the ash-pit, where it enters the mass of ignited coal in the fire-box and is burned, and at the same time may be used to operate an air-injector for 40 feeding air to the furnace.

What I claim is—

1. In combination with a boiler-furnace or fire-box, a superheater located within the furnace, so as to be subject to the most intense heat

of the same, a pipe-connection between the boiler and the superheater, an air-injector for said fire-box or furnace, having a pipe-connection with the outlet end of the superheater, which pipe-connection is of less bore or diameter than that of the superheater coils or pipes, 45 whereby the steam-supply in the superheater is resolved into its gaseous elements for operating said injector, substantially as set forth.

2. In combination with a boiler-furnace or fire-box, a superheater located in said fire-box, 50 a pipe-connection having a cut-off between the boiler and superheater, and an air-injector for said fire-box, having a pipe-connection with the outlet end of the superheater, which pipe connection is of less diameter than that of the superheater coil or pipe, substantially as set forth.

3. In combination with a boiler, a furnace, a superheater located within the furnace, so as to be subject to the heat of the same, a pipe-connection between the boiler and the superheater, 55 an air-injector for said furnace, and a pipe-connection between the outlet end of the superheater and the air-injector, which pipe-connection has a bore smaller than that of the superheater coils or pipes, whereby the steam-supply in the superheater is decomposed into 60 its gaseous elements for operating said injector, substantially as set forth.

4. The combination of a boiler-furnace, a steam-pipe leading from the steam-space of the 75 boiler, a superheater connected with said steam-pipe and with the ash-pit by a reduced connection, which retards the flow from the superheater and causes the heat of the fire-box to disassociate the gaseous elements of the steam 80 in the superheater in the manner substantially as described, and for the purpose set forth.

In testimony whereof I affix my signature in presence of two witnesses.

ELIJAH B. CORNELL.
